UNITED STATES PATENT OFFICE.

CARL J. WALLACE, OF SPRINGFIELD, OHIO

DISTRIBUTER FOR AUTOMOBILE-CIRCUITS.

1,244,927.

Specification of Letters Patent. Patented Oct. 30, 1917.

Application filed July 31, 1915. Serial No. 42,990.

To all whom it may concern:

Be it known that I, CARL J. WALLACE, a citizen of the United States, residing at Springfield, in the county of Clark and State of Ohio, have invented certain new and useful Improvements in Distributors for Automobile-Circuits, of which the following is a specification, reference being had therein to the accompanying drawing.

10 This invention relates to distributors for automobile circuits. The object of the invention is to provide a very simple and compact arrangement of circuits and controlling devices which will enable these circuits to be controlled in groups and individually in a convenient manner. To this end it is a further object of the invention to provide the device with a main switch to control one group of circuits, such as the lighting and 15 horn circuits, and to provide a second group of circuits, such as the engine circuits, with a separate controlling device, the circuits of each group being provided with individual controlling devices, thus enabling 20 either group of circuits as a whole to be controlled independently of the other group and enabling the individual circuits of each group to be controlled independently of each other when the main controlling device is 25 in its closed position. It is also an object of the invention to provide a controlling mechanism for the engine circuits whereby a single device will control the starter circuit and both ignition circuits and whereby 30 the ignition circuits and the starter circuit can be controlled independently of each other. It is a further object of the invention to mount these mechanisms within a casing with only the actuating members for 35 the several controlling devices exposed on the exterior of said casing.

40 In the accompanying drawings, Figure 1 is a top, plan view of the distributor with the top plate and the operating handle for the main switch removed; Fig. 2 is an elevation of the distributor looking toward the left on Fig. 1, with the upper part thereof in section taken centrally through the same and with the lower portion of the 45 casing adjacent the right broken away and partly in section; Fig. 3 is a horizontal, sectional view taken on the line $\alpha\alpha$ of Fig. 2 looking in the direction of the arrows and showing the main switch open; Fig. 4 is 50 a transverse, sectional view taken on the line $\gamma\gamma$ of Fig. 2 and looking in the direction of the arrows; Fig. 5 is a section taken on the line $a\alpha$ of Fig. 4 and looking in the direction of the arrows; Fig. 6 is a sectional view taken on the line $b\beta$ of Fig. 4 and looking in the direction of the arrows; Fig. 7 is a detail view of the starter switch; Fig. 8 is a transverse, sectional view taken on the line $w\omega$ of Fig. 2 and looking in the direction of the arrows; and Fig. 9 is a diagram of the circuits.

55 This application is a continuation in part of the application filed by me October 4th, 1913, Ser. No. 793,367, on which Letters Patent 1,177,976 were granted April 4th, 1916. Matter herein shown and described which is also shown and described in my copending application filed July 31st, 1915, Ser. No. 42,989, is claimed in the latter.

60 In these drawings I have illustrated one embodiment of my invention.

65 As here illustrated the distributing device comprises a casing of bakelite or hemit 1 having mounted therein the various circuit controlling devices. This casing comprises a bottom wall or base 2 provided with a central opening 3 through which the various conductors may be led to their controlling devices. The casing is closed at its 70 upper end by a top wall or cap 4 having therein a bearing 5 in which is journaled an actuating device or handle 6 for the main switch, which will be hereinafter described.

75 Supported within the casing is a drum 7 which forms a support for certain of the controlling devices and also constitutes a core for the resistance winding 8, as will hereinafter appear. This drum may be 80 supported within the casing in any suitable manner, but is here shown as formed integral with a plate or partition 9, the lateral edges of which extend beyond the periphery of the drum and are mounted between the 85 upper and lower portions of the casing, which, in the present instance, is divided into two parts. This partition serves also to divide the casing into upper and lower compartments. Both the partition 9 and the bottom wall of the drum are provided with openings 10 and 11 to permit of the free circulation of air through and about the drum. Mounted within the drum and preferably on the bottom wall thereof is a 90 main switch which, as here shown, comprises a fixed contact member 12 which is in 95 100 105 110

the form of a flat curved plate supported by and arranged above the connector plate 13 which is mounted on the bottom wall of the drum 7 and is electrically connected at 14 with the battery lead 15. The usual source of current for automobile electrical systems is a storage battery and it is contemplated that the present device will be used with such a system but it will also be understood that its use is not limited to storage battery systems but it may be used in connection with any suitable source of supply for electric current and the term "battery lead" as herein used will include the conductor leading from any such source of supply. Cooperating with the fixed contact member 12 of the main switch is a movable contact member 16 which is here shown as carried by a stud 17 rotatably mounted in the bottom wall of the drum 7 and as formed of two resilient arms adapted to engage the opposite sides of the contact plate and to be moved into and out of engagement therewith, the edges of the arms being flared to facilitate their reengagement with the contact member after they have been moved out of contact therewith. The rotatable stud 17 is connected at its upper end with a block of insulating material 18 which is rotatably mounted in the partition 9 and has secured thereto a connecting device or rod 19 extending through the upper compartment of the casing and connected with the actuating handle 6, by means of which the main switch may be manipulated.

Leading from the drum 7 is a head light circuit 20 which also includes the resistance winding 8 which is mounted on the core or drum 7. This head light circuit is provided with a plurality of separated contact points 21, 22 and 23 arranged to cut in different quantities of the resistance windings and thus regulate the brilliancy of the head lights. Cooperating with these contact points is a movable contact member or arm 24 which is secured to the stud 17 so as to move with the movable member of the main switch and is electrically connected with the movable member of the main switch. Consequently, the current passes from the movable member of the main switch through the arm 24 and from the selected contact point to the head light circuit. The contacts 21, 22 and 23 are so arranged with relation to the fixed contact member of the main switch that when the movable member or arm 24 of the controlling device for the head light circuit is in contact with any one of these points the movable member of the main switch will be in contact with the fixed contact member of that switch. When the handle 6 is moved to the limit of its movement in one direction both of the movable contact members will be moved out of engagement with the fixed contact members and the

whole lighting system will be dead. Arranged between this extreme position and the contact member 23 is an intermediate point 25 at which the main switch may be closed without closing the head light circuit. The contact point 25 serves to hold the switch and controlling device in this position.

The stud 17 which carries the movable member of the main switch is electrically connected by means of a band or conductor bar 26 with a connecting bolt or tie rod 27 which also serves as a conductor and is connected at its upper end with a contact plate 28 having a portion arranged in the path of the plunger 29 of a push button which is held normally in its outer position by a spring 30 and is connected with the horn circuit 31, thus enabling this horn to be sounded whenever the main switch is closed. This contact plate 28 extends inward and is connected at 32 with a plate 33 turned upward to form a support for a transverse member 34 which, in the present instance, is formed integral with the contact plate. This member 34 extends transversely of the casing to points near the opposite sides thereof and is provided at its respective ends with downturned portions 35 and 36 which constitute contact members. Arranged adjacent to but spaced away from the contact members 35 and 36 are other contact members 37 and 38 which comprise resilient arms and are connected, respectively, with the circuit for the dash and tail lights, which are preferably connected in series and with the circuits for the side lights or lights within the car. The casing is provided adjacent to each pair of contacts with a bearing, 39 and 40, in which is rotatably mounted a stud 41 having at its inner end a transverse head 42 of such length that when turned into horizontal position the ends thereof will engage the respective contact members and establish electrical connection between them, and when the head is turned in a vertical position it will lie between and out of engagement with the contact members. The inner end of the bearing is flared and each stud is provided with a spring 43 to move the same outward and thus draw the edge of the transverse head into the flared recess in the bearing to hold the same in its inoperative position. The studs are provided with handles or wheels 44 by means of which they may be rotated, the rotation of the studs causing their heads to travel along the flared edges of the recesses in bearings against the tension of the springs.

The engine circuits, that is, the starter and ignition circuits are placed under individual control subject to a main controlling device, the operation of which serves to make or break the several circuits. As here shown all the controlling devices for 1.

the engine circuits are mounted in the lower part of the casing and the operable parts thereof are carried by the base 2 of the casing. In the present construction there are 5 two ignition circuits, one connected with a dry battery, although obviously a storage battery could be used, and the other connected with a magneto. The starter circuit is connected with the storage battery in advance of the main switch for the lighting circuits so that it is not affected by the position of that switch. As here shown it is connected with the connector plate 13 by means of a stud 45 and a plate 46, which latter is connected with and preferably carries the fixed contact member of a switch forming a part of the main controlling device. As here shown a fixed contact member, 47, comprises two resilient fingers 20 pending from the plate 46 adapted to receive between them a blade or movable contact member 48 which is pivotally mounted on brackets 49 carried by the base 2 and is held normally out of engagement with the 25 fixed contact member by means of a spring 50. Connected with the movable contact member or blade 48 through the medium of its pivot pin is a conductor bar 51 which leads to a resilient contact member or finger 52 forming a part of the starter switch. 30 Coöperating with the finger 52 is a second resilient finger or contact member 53 which is connected with a conductor 54 leading to the starter. A push button 55 is slidably 35 mounted in the base 2 of the casing, in which the contact members 52 and 53 are mounted, and has a stem or plunger 56 adapted to enter the space between and establish electrical communication between 40 the contact members 52 and 53. A spring 57 holds the plunger normally in its inoperative position.

The ignition circuits comprise a main conductor 58 leading to the ignition devices 45 and adapted to be connected in either of two circuits, the one leading to the dry cells and the other to the magneto. As here shown, the conductor 58 is adapted to be electrically connected with a pivoted arm 59 to which is secured a handle 60, by means of which the arm can be moved into engagement either with a contact point 61 connected by a conductor 62 with the dry cells or into engagement with a contact point 63 55 connected by a conductor 64 with the magneto. A third point is provided, as shown at 65, to form a stop to retain the movable contact member 59 in a neutral position in which the ignition circuit is broken. The handle 60 travels along a suitable gage 66 to indicate the position of the contact member 59. Means are provided for placing the ignition circuits under the control of the main controlling device and to this end I 65 have established connection between the ig-

nition circuit 58 and the movable contact member 59 through the medium of a circuit breaker and closer comprising a resilient finger 67 connected with the conductor 58 and a movable contact member or wiper 68 70 secured to the pivoted contact member 59 and moving therewith, the width of this wiper 68 being such that it can engage the resilient contact member 67 when the movable contact arm 59 is in any one of its 75 three positions. The blade or movable contact member 48 of the main controller is provided with a part 70 extending beyond its axis and having means for moving the resilient contact member 67 into and out of 80 engagement with the wiper 68. This means preferably comprises two insulated pins 71 and 72 so arranged that when the movable contact member is moved into its inoperative position the pin 72 will lift the contact 85 member 67 away from the wiper and when the blade or contact member 48 is moved into its operative position the pin 71 will move the resilient contact member 67 into engagement with the wiper 68. The resiliency of the contact member 67 will serve 90 to return the same to its operative position in engagement with the wiper but in order that this return movement may be positive I prefer to provide the pin 71 for this purpose. Any suitable means may be provided for actuating the blade or movable contact member of the main controlling device. As here shown I have provided a removable key for this purpose which 95 consists of a stem 73 having on its outer end a finger piece or handle 74 and provided at its inner end with a bit or lip 75. The base 2 of the casing is provided with a thickened portion 76 in which is formed a slot 100 105 communicating with a recess 77 into which the lower edge of the blade extends when the latter is in its inoperative position. The slot is provided at one end with a depression or groove which forms a bearing 110 for the stem 73 and when the bit of the key has been passed through the slot into a position beneath the blade 48 the key can be rotated in this bearing and the bit caused to engage the lower edge of the blade and 115 move the same into its operative position, thus closing the engine circuits. By separating the control of the engine circuits from the lighting circuits the one can be controlled independently of the other and 120 the engine circuits can be interrupted and the machine effectually locked against operation by the removal of the key, or actuating device for the master controlling device. 125

While I have shown and described one embodiment of the invention it will be understood that this has been chosen for the purposes of illustration only and that I do not desire to be limited to the details of 130

construction shown and described, for obvious modifications will occur to a person skilled in the art.

Having thus fully described my invention, what I claim as new and desire to secure by Letters Patent, is:—

1. In a system of distribution, a plurality of sources of electrical energy each having a fixed contact member, a lever of conducting material adapted to be moved into engagement with either one or the other of said contact members, an electrical device provided with a movable contact member adapted to engage and disengage said lever, and means for actuating said movable contact member.
2. In a controlling device for engine circuits, a starter circuit, an individual circuit breaker and closer therefor, a plurality of ignition circuits leading to separate sources of electric current, separate fixed contact members for said ignition circuits, a single movable contact member co-operating with both said fixed contact members for said ignition circuits, a second circuit breaker and closer interposed between said movable member and the ignition devices and comprising a part carried by said movable member and a part movable into and out of engagement with said part carried by said movable member, a second circuit breaker and closer in said starter circuit comprising a pivoted member having a part extending beyond its axis and provided with insulated devices for moving the last-mentioned member of said second circuit breaker and closer

for the ignition circuits into and out of engagement with the other part of said second circuit breaker and closer.

3. In a system of distributors, a casing having a base, a plurality of circuits, circuit breakers and closers for said circuits, one of said circuit breakers and closers comprising a movable member pivotally mounted on said base and having a part arranged to actuate the other circuit breaker and closer, said base having an opening leading to a point adjacent the movable member, and an actuating device adapted to be inserted in said opening to actuate both of said circuit breakers and closers, and an additional circuit breaker and closer in each circuit operable independently of the first-mentioned circuit breakers and closers.

4. In a controlling device, a plurality of sources of electrical energy provided with conductors having fixed contact members, an electrical device provided with a movable contact member, a lever provided with arms adapted to engage said movable contact member and to be moved into engagement with either of said fixed contact members, a circuit, a circuit breaker and closer for said circuit comprising a movable member, and means on said last-mentioned movable member in engagement with the first-mentioned movable member, whereby they are simultaneously controlled.

In testimony whereof, I affix my signature.

CARL J. WALLACE.
